BOOK BINDING AND METHOD OF MAKING
THE SAME

Charles L'Enfant, Brooklyn, N. Y.

Application April 20, 1933, Serial No. 666,968

6 Claims. (Cl. 281—35)

This invention relates to an improved binding or cover for books, and more particularly to what is generally referred to as a limp leather binding.

5 The invention has for its general object and purpose to provide a new method of making such bindings, whereby the marginal edge portions extending beyond the edges of the book leaves will retain an inwardly bent position in angular relation to the opposite sides or covers of the book.

It is very desirable in certain kinds of books such, for instance, as bibles, that the extended edges of the book covers shall retain a more or less fixed angular relation to the planes of said 15 covers and in over-hanging relation to the gold edges of the book leaves to thereby afford more or less protection to the latter, and also minimize cracking or disfigurement of the edge portions of the book covers, due to frequent and excessive 20 flexing of the same.

It is also a further general object of the invention to provide an improved limp leather book cover as a new article of manufacture which may be rapidly manufactured at very low cost in labor 25 and materials.

With the above and other objects in view, the invention consists in the improved book binding and method of making the same, as will be hereinafter more fully described, illustrated in the 30 accompanying drawing and subsequently incorporated in the subjoined claims.

In the drawing wherein I have shown one simple and practical embodiment of the invention, and in which similar reference characters designate corresponding parts throughout the several views,

Figure 1 is a plan view of the cover or binding sheet of leather, imitation leather or other material, having flexible reinforcing parts and a lining sheet applied thereto;

Fig. 2 is a similar view of the completed binding, parts thereof being broken away;

Fig. 3 is an enlarged sectional view taken on the line 3—3 of Fig. 2;

Fig. 4 is a similar view of a modified construction; and

Fig. 5 is a perspective view of a book provided with my new binding.

Referring in detail to the drawing, 5 designates the body sheet of the flexible binding which may be of real or imitation leather or other suitable flexible material, and is cut to the predetermined size and shape. Upon the inner face of this binding, and at opposite sides of its center, reinforcements of paper or other flexible material generally indicated at 6 is secured by means of a suitable adhesive. The opposed spaced apart inner edges of these reinforcing sheets shown at 7 extend in parallel relation to each other, while the 50 remaining edges of each reinforcing sheet are

disposed in suitable spaced parallel relation inward from the corresponding edges of the body sheet 5. If desired, the two sections 6 of reinforcing material may be cut from a single sheet, remaining integrally connected at their upper and lower ends by narrow strips of the material, as indicated at 6'. In spaced parallel relation to each of the upper and lower end edges of the reinforcing sheets 6, one or more longitudinal slots 8 are provided therein, and in spaced relation 70 from the outer vertical edge of each reinforcing sheet similar slots 9 are formed therethrough.

After the slotted paper reinforcing sheets have been applied to the body 5 of the binding, a finishing or lining sheet 10 of fabric or other suitable flexible material is then applied over the reinforcing sheets and adhesively secured thereto, said lining sheet extending to the extreme outer edges of the reinforcing sheets.

The projecting edge portions of the body sheet 5 are now turned inwardly and adhesively secured upon the edges of the lining sheet 10 as indicated at 11. The central portion of the finishing sheet 10 is cut out as shown at 12 to expose the inner face of the binding 5, to which the signatures of the book are secured at their back edges, in the manner now commonly employed in this art.

The binding, as above described, is now completed by forming a groove, depression or score 90 indicated at 13 in the fabric finishing sheet 10 and in line with the slots 8 and 9 in the reinforcing sheets 6. A second relatively light score line 14 is then impressed in the outer edge of the fabric finishing sheet 10 at the inwardly 95 turned edges of the body sheet 5.

After the book signatures have been assembled and properly secured to the inner face of the back of the binding, the edges of the latter are then angularly bent along the score line 13 100 so that the marginal edge portions of the binding of uniform width will extend at an appreciable angle to the planes of the cover forming portions of the binding which extend over the book leaves. The gold leaf applied to the edges of the book leaves, as is common in bibles and other books of better quality, is thus protected. Also, due to the provision of the slots 8 and 9 in the paper reinforcing sheets 6, these edge portions of the binding will not return to their former positions 110 substantially in the planes of the book leaves. Thus, in the use of the book, these edges of the binding maintaining their angular inwardly bent relation to the book covers, will not be subjected to excessive flexure with liability of cracking or 115 marring of the outer surfaces of the sides of the book cover at their juncture with said edge portions.

In Fig. 4 of the drawing, I illustrate a slightly modified form of my invention, in which instead 120

of using the separate paper reinforcing sheets 6, the body of the binding is of relatively thick leather or other flexible material. On the inner side of this binding sheet 5' in spaced relation to its edges, portions of the material are cut out or removed to provide the longitudinal grooves as at 8' therein corresponding to the slots 8 and 9, while the marginal edge portion of the material on the inner face of said sheet is also removed as indicated at 15, so that said edges are relatively thin. In this case, the inner facing sheet 10' is then adhesively secured in place and extends over the entire relatively thick portion of the body sheet 5'. The thin edges 15 of the body sheet are then inwardly folded and adhesively secured to the thicker portion of said sheet. The marginal edge portions of the body and facing sheets are then bent inwardly along the grooves 8', so that without additional reinforcement, they will retain their positions substantially in predetermined angular relation to the cover forming side portions of the binding.

From the foregoing description considered in connection with the accompanying drawing, the construction, and method of making my improved book binding will be clearly and fully understood. It will be evident that the method of manufacturing is exceedingly simple and may be accurately and rapidly carried out so that such book bindings can be produced in large quantities with a minimum of labor and with a minimum of expense incident to the use of labor and materials.

While I have herein shown and described several simple and practical embodiments of the invention, it will nevertheless be understood that the same may also be embodied in various other alternative forms, and I accordingly reserve the privilege of resorting to all such legitimate changes therein as may be fairly incorporated within the spirit and scope of the appended claims.

I claim:

1. A binding for books comprising a body sheet of flexible material, flexible reinforcing sheets secured to the inner face of said body sheet on the cover forming portions of the latter and having outer end and side edges inwardly spaced from the edges of the body sheet and provided in spaced parallel relation thereto with longitudinally extending slots, an inner facing sheet adhesively secured upon said reinforcing sheets, the marginal edges of the body sheet being inwardly folded over the edges of the facing sheet and adhesively secured thereto, said facing sheet having a continuous depression or score line therein in spaced relation to its edges and in line with the slots in the reinforcing sheets, whereby the marginal edge portions of the binding may be bent along said score line and said slots, to remain in a position at an appreciable angle with respect to the planes of the cover forming portions of the binding.

2. A flexible binding for books comprising a body sheet of flexible material having relatively thick cover forming portions with parts of the material thereof removed along lines extending in parallel relation to the marginal edges of said cover forming portions of the binding to render said marginal edges, after flexing, incapable of resuming their original positions by force of inherent elasticity, whereby said marginal edges of the binding may be angularly bent to remain

in a permanent position at an appreciable angle with respect to the planes of the respective cover forming portions of the binding.

3. The method of making a flexible binding for books which consists in cutting a sheet of flexible material to provide a body forming blank of predetermined size and shape, then cutting reinforcing sections of flexible material, each corresponding in shape to one of the cover forming portions of said body sheet and providing slots through said reinforcing sheets in spaced relation to the marginal edges thereof, then adhesively securing said reinforcing sheets to the cover forming portions of said body sheet and in inwardly spaced relation to the edges of the latter, then adhesively securing an inner facing sheet upon said reinforcing sheets and over the slots therein, then folding the edge portions of the body sheet inwardly and adhesively securing the same to said reinforcing sheet, then scoring or grooving said facing sheet to provide a continuous groove therein in spaced relation to its marginal edges and in line with the slots in the reinforcing sheets, whereby, after securing the book leaves to said body sheet between the reinforcing sheets, the marginal edge portions of the binding may be bent along said score line and the slots in the reinforcing sheets to permanent positions in inwardly projecting angular relation to the cover portions of the binding and overlying the edges of the book leaves.

4. A resilient binding cover for books containing a stiffening and strengthening sheet element, the cover with said element having projecting marginal portions bendable angularly with respect to the body of the cover to lie in close relation to the edge of the book for protecting the edges of the signatures thereof, the material of said element along lines corresponding with the inception of the marginal portions having openings therein whereby to reduce inherent resiliency and render said marginal portions permanently incapable of resuming their original unbent positions after they have been bent to position for protecting the edges of the signatures of the book.

5. In a binding cover for books which includes a resilient body sheet having attached thereto a resilient reinforcing sheet to stiffen and strengthen the same, said sheets being of a size to form inwardly bent protective marginal portions for the book signatures at the end and side edges of the book, said reinforcing sheet having therein spaced openings at the inception of the bends at the end and side edges of the book to afford thereat a permanent inherent reduction in resiliency whereby when the marginal portions are bent inwardly to protective positions they will remain substantially in such inwardly protective positions.

6. A binding cover for books comprising a body sheet and a reinforcing sheet which stiffens and strengthens the same, both sheets being of inherently resilient character and of a size to form inwardly bent protective marginal portions for the book signatures at the end and side edges of the book, the reinforcing sheet at the inception of the bends to produce the marginal portions having spaced slots therein to permanently reduce inherent resiliency, said slots in their aggregate being equal to or greater than, the aggregate of the non-slotted material.

CHARLES L'ENFANT.
